[57] CLAIM

The ornamental design for a top shell for expansion bracelet link, as shown and described.

DESCRIPTION

FIG. 1 is a perspective view of a top shell for expansion bracelet link showing my new design;

FIG. 2 is a top plan view thereof;

FIG. 3 is a side elevational view thereof;

FIG. 4 is a bottom plan view thereof;

FIG. 5 is an end elevational view thereof; and

FIG. 6 is a plan view of a plurality of links shown in a position of use.

FIG. 1

FIG. 2

FIG. 3

FIG. 4

FIG. 6

FIG. 5
